[57] **CLAIM**

The ornamental design for a seat cushion for back support, as shown and described.

DESCRIPTION

FIG. 1 is a perspective view of a seat cushion for back support, showing my new design;
FIG. 2 is a front elevational view thereof;
FIG. 3 is a rear elevational view thereof;
FIG. 4 is a right side elevation view thereof, the left side elevation view being a mirror image thereof;
FIG. 5 is a top plan view thereof; and,
FIG. 6 is a bottom plan view thereof.

FIG 1

FIG 2

FIG 3

FIG 4

FIG 5

FIG 6
